UNITED STATES PATENT OFFICE.

WILLIAM C. HOMAN, OF MERIDEN, CONNECTICUT, ASSIGNOR TO EDWARD MILLER & COMPANY, OF SAME PLACE.

WICK-ADJUSTING DEVICE.

SPECIFICATION forming part of Letters Patent No. 434,929, dated August 26, 1890.

Application filed March 6, 1890. Serial No. 342,919. (No model.)

To all whom it may concern:

Be it known that I, WILLIAM C. HOMAN, a citizen of the United States, residing at Meriden, New Haven county, Connecticut, have 5 invented a new and useful Improvement in Wick-Adjusting Devices, of which the following is a specification.

My invention relates to that class of wick-adjusting devices used in Argand lamps in which a tubular wick encircles a vertically-movable sleeve, and is intended to provide a cheap and effective means of securing the wick to the sleeve.

In the accompanying drawings, Figure 1 is 15 an elevation of an Argand lamp partly broken away to show the interior mechanism. Figs. 2 and 3 show the wick-clamp detached from the lamp.

The same letters refer to like parts in the 20 several views.

A designates a lamp fount or body; B, an inner wick-tube; C, a wick-adjusting sleeve; C', a draw-bar; D, a wick; E, a wick-clamp, and e e' radially-projecting ends of the clamp E.

25 The example of my invention shown in the drawings is constructed and operated as follows: The lamp-fount A, inner wick-tube B, and wick-adjusting sleeve C may be of usual or any convenient form. The wick D is slipped over sleeve C and so as to have frictional contact therewith. This frictional contact is seldom sufficient when the lamp is in service and the wick saturated with oil to secure the adhesion of the wick to the vertically-moving sleeve. It has therefore been customary to provide the sleeve with outwardly-projecting teeth or the like adapted to engage with the wick. These are objectionable, as apt to tear the wick and as interfering with the removal of the old wick when a fresh one is necessary. Instead of or in addition to these teeth, bands or clamps of various forms have been provided. These have been secured to the wick-sleeve or provided 40 with a lock for attaching their ends together. These are objectionable, as requiring more skill to detach and reattach than is possessed by many inexpert consumers.

My device, as shown, is a band E, of resilient wire or other material, bent into the form 50 of a circle, with overlapping ends and provided at its extremities with radially-projecting portions e e'. The circle is of such a normal circumference as to hug the wick with sufficient force to secure its adhesion to the 55 sleeve when the latter is vertically adjusted. To wick the lamp, slip the wick D over the sleeve C, as usual, open the clamp or band E, and abut the projecting portions e e' against each other, as shown in Fig. 3 of the drawings, pass the clamp E over the wick to its proper place, and release the ends e e' from contact, when the clamp will, because of its resilience, contract to the form shown in Fig. 2 and clasp the wick D to the sleeve C, as 60 required. To remove the clamp from the wick, press the ends e e' together with the finger and thumb, thereby increasing the circumference of the clamp E and allowing it to be easily slipped from the wick. I do not of 65 course consider myself limited to the particular form of construction or material shown or described.

What I claim as my invention, and desire to secure by Letters Patent of the United States, 70 75 is as follows:

1. A wick-clamp of resilient material substantially in the form of a circle, with ends normally overlapping and adapted to abut against each other when the clamp is opened, 80 substantially as described.

2. A wick-clamp of resilient material substantially in the form of a circle, with radially-projecting ends normally overlapping and adapted to abut against each other when the clamp is opened, substantially as described.

3. A wick-clamp formed of one piece of resilient wire substantially in the form of a circle, with ends normally overlapping and adapted to abut against each other when the clamp is opened, substantially as described.

WM. C. HOMAN.
